(57) **CLAIM**

The ornamental design for table storage system, as shown and described.

DESCRIPTION

FIG. 1 is a front perspective view of a second embodiment of a table storage system;

FIG. 2 is a front elevation view of the second embodiment of a table storage system;

FIG. 3 is a side elevation view of the second embodiment of a table storage system; and,

FIG. 4 is a bottom plan view of the second embodiment of a table storage system.

The broken lines in FIGS. 1-4 are shown for environment and form no part of the claimed design.
